UNITED STATES PATENT OFFICE.

HOLDA A. HACKER, OF ONEONTA, NEW YORK.

RAIL-FASTENING MEANS.

1,287,677.

Specification of Letters Patent. Patented Dec. 17, 1918.

Application filed July 10, 1918. Serial No. 244,178.

To all whom it may concern:

Be it known that I, HOLDA A. HACKER, a citizen of the United States, residing at Oneonta, in the county of Otsego, State of New York, have invented certain new and useful Improvements in Rail-Fastening Means; and I do hereby declare the following to be a full, clear, and exact description of the invention, such as will enable others skilled in the art to which it appertains to make and use the same.

The present invention relates to new and useful improvements in rail fastening means, more particularly of that type adapted for association with concrete or other ties whose character prevents the driving of securing spikes thereinto.

It is in general the object of this invention to simplify and otherwise improve the structure of devices of this character, particularly with respect to their attachment to a concrete tie in a manner providing an adjustment of the gripping action of the device on the rail.

A more detailed and important object resides in the provision of a fastening device which may be actuated for gripping relation or released from such relation without the use of nuts or wedges and wherein the gripping pressure set up in the application of the device to a rail serves to hold the device in gripping position.

With the above and other objects and advantages in view, the invention resides more particularly in the novel combination, formation and arrangement of parts herein-after described and particularly pointed out in the appended claims.

In the accompanying drawings:

40 Figure 1 is a plan view of the device applied to a rail and tie.

Fig. 2 is a side elevational view of what is shown in Fig. 1.

Fig. 3 is a sectional view on the line 3—3 of Fig. 1.

Fig. 4 is a sectional view on the line 4—4 of Fig. 1.

Fig. 5 is a perspective view of the locking member.

50 Referring now more particularly to the drawings, there is shown a concrete tie 10 having positioned thereon the rail 11.

Embedded vertically in the tie at one side of the rail flange is a sleeve 12 having its upper end flush with the top of the tie and having its lower end terminating short of

the bottom of the tie and communicating with a nut receiving recess 13 in said bottom. An anchor plate 14 is embedded horizontally in the tie at the bottom of the sleeve. Slidably passed through the sleeve is a bolt 15 having its lower end threaded in a nut 16 in the recess 13 and engaging against a leather or other fabric washer 17 interposed between it and the anchor plate 14. The other end of the bolt extends above the tie and is bent to form a hook portion 18 for holding the rail engaging member of the device.

This rail engaging member comprises an angular lever having a relatively wide and strong short arm 19 and a long arm 20 curved in the direction of the short arm and having a rail engaging foot 21 at its free end. A pivot arm 22 extends laterally from the lever and is engaged in the hook portion 18 at its inner end while its outer end is engaged in a guide member formed of a single length of metal having its intermediate portion bent to form a receiving eye 24 and its end portions projecting upwardly from the tie, in which they are embedded, the extremities of said end portions being bent apart at 25 for anchor engagement in the tie.

An exceedingly simple locking structure has thus been provided. In operation, the parts are so arranged, particularly by adjustment of the bolt 15 in the sleeve 12, that the distance from the pivotal axis of the angle lever and the top face of the base flange of the rail 11 seated on the tie is slightly less than the distance from said axis to the end of the lever arm 19. Thus upon swinging the long arm 20 of the lever 95 downwardly, the arm 19 will move under the pivotal axis of the lever in sliding engagement with the base flange of the rail, and exerting a considerable clamping pressure. As the arm 19 moves from under the axis of the lever at its side remote from the arm 20, the arm 20 engages the base flange of the rail and thus the clamping pressure set up serves to lock the parts against releasing movement, some very slight yielding to 100 permit this operation being afforded by movement of the hook bolt, compressing the washer 17. To release the rail, it is merely necessary to lift the lever arm 20 and swing the arm 19 under the axis of the lever and 105 out of the lever and out of engagement with the base flange of the rail. The lever may

be most readily detached and replaced should it become broken.

What is claimed is:

1. The combination with a rail tie, of a bearing member, and an angle lever pivotally connected with said bearing member, said lever including a relatively short arm engageable with a rail base flange on the tie and movable transversely of the axis of the lever in such engagement, and a relatively long arm engageable with the rail base flange upon movement of the short arm transversely past the pivotal axis of the lever.
- 15 2. The combination with a rail tie, of a bolt upstanding therefrom and having its upper end bent in hook shape, an angle lever including a relatively long arm and a relatively short arm and a pivot pin projecting laterally from the lever for engagement in the hook portion of the bolt, said short arm of the lever being engageable with the base flange of a rail on the tie and movable past the pivotal axis of the lever upon downward swinging movement of the long arm, to engage the base flange.
- 20 3. The combination with a rail tie, of a bolt upstanding therefrom and having its upper end bent in hook shape, an angle lever including a relatively long arm and a relatively short arm, a pivot pin projecting laterally from the lever for engagement in

LESTER HOWE.

In testimony whereof, I affix my signature, in the presence of two witnesses.

HOLDA A. HACKER.

the hook portion of the bolt, said short arm of the lever being engageable with the base flange of a rail on the tie and movable past the pivotal axis of the lever upon downward swinging movement of the long arm, to engage the base flange, and means for adjustably connecting the bolt with the tie.

4. The combination with a tie provided with a vertical passage therethrough and with a nut receiving recess in its bottom communicating with its passage, of an anchor plate embedded in the tie at the junction of said passage and nut recess, a bolt extended through the passage and anchor plate, a nut threaded on the lower end of the bolt in said recess, said bolt having its upper end bent in hook shape, an angle lever including a relatively long arm and a relatively short arm, and a pivot pin projecting laterally from the lever for engagement in the hook portion of the bolt, said short arm of the lever being engageable with the base flange of a rail on the tie and movable past the pivotal axis of the lever upon downward swinging movement of the long arm, to engage the base flange.

In testimony whereof, I affix my signature, in the presence of two witnesses.
